GOLF BAG

Harry D. Gihon, III, Trenton, N. J.

Application February 17, 1937, Serial No. 126,175

1 Claim. (Cl. 150—1.5)

This invention relates to containers and has for an object the improvement in the manner of construction of the bottoms of containers.

This invention has for an object the construction of an inexpensive and improved bottom member for golf bags, so that a maximum of strength may be obtained with a minimum of operative steps in the manufacture thereof.

The invention is illustrated in the accompanying drawing in which one embodiment of the golf bag bottom is shown and in which like reference characters refer to like parts.

In the drawing:

Fig. 1 shows in cross section the golf bag bottom,

Fig. 2 shows in plan the insert used in Fig. 1, and

Fig. 3 shows a modified form of insert.

In the process of making this golf bag bottom, the insert to be used is first selected as to shape and size. For instance, as shown in Figs. 1 and 2, a circular insert 4 may be chosen. This insert 4 may be of wood, metal, fibre, or of any suitable composition material, and is beveled as shown at 5. Then by means of suitable adhesive material, a covering 6 of suitable material such as leather or fibre, is pasted to the bottom side of the insert and is shaped around the beveled part of the insert with edges extending above the top part of the insert. In a similar manner a suitable covering is secured to the top of the insert with edges of the covering extending beyond the edges of the top of the insert. The extending edges of the top and bottom coverings lie adjacent each other as shown in Fig. 1.

Next the member 8, which may be of fibre or leather and which may be covered as shown at 9 in the case of fibre, is sewn at its lower edge to the upstanding edges of the coverings 6 and 7 by means of the lines of stitching shown at 10 and 11. At the beginning of this operation the member 8 is rectangular in shape and as the sewing progresses assumes the circular shape of the insert. The sewing continues as shown to fasten together the overlapping edges 12 and 13 of the member 8. There is but the one sewing operation in which the member 8 is fastened to the upstanding edges of the insert coverings and in which the edges 12 and 13 are sewed to each other by the continuing stitches of the lines of sewing used in coverings 6 and 7.

It will be obvious that other means, such as rivets etc., which while not as desirable as sewing, may be used to fasten the member 8 to the coverings 6 and 7 and the edges 12 and 13 to-

gether. If, as pointed out, there is a single continuous sewing operation, then an inspection of the article would show the stitches fastening together the edges 12 and 13 to be in continuation of the lines of stitches 10 and 11, thus showing, from an inspection of the article the steps in the manufacture thereof, including that the overlapping edges 12 and 13 were joined together after the member 8 was fastened to the coverings 6 and 7. However, if rivets are used as the fastening medium, or if a non-continuous sewing operation is used, that is, after the member 8 is sewed to the coverings 6 and 7, the thread is broken and a new and separate seam used to join the edges 12 and 13, then an inspection of the finished product would not disclose whether the member 8 was secured to the coverings 6 and 7 before or after the edges 12 and 13 were joined together. The applicant considers it essential to the practice of his invention that the first step be that of joining the member 8 to the coverings 6 and 7 as in that way there is always positive assurance that the finished ring of the member 8 will fit tightly around the coverings 6 and 7.

The completed bottom may then be fastened to a conventional member shown in dotted lines at 14 and comprising the upstanding part of any golf bag. The fastening may be by sewing or by other means.

To the underside of the finished golf bag bottom may be secured the conventional protecting buttons 15 by means of rivets or the like. Any of the conventional protecting means, such as the L shaped metal corners may also be added to the bag bottom, preferably at the overlapping of the edges 12 and 13.

As shown at 16 any shape of insert may be used in the manufacture of the bottom. In Fig. 3 is shown an insert of elliptical outline and this lends itself to the process of manufacture herein disclosed, as readily as does the circular insert. Obviously with any shape insert, the edges thereof may be beveled or not as desired. With a shape of insert other than circular, there is no change in the member 8 at all, the only requirement being that it be long enough to go around the insert and overlap on itself. The inserts shown in plan in Figs. 2 and 3 are on a smaller scale than the one shown in Fig. 1.

I claim:

A golf bag bottom unit adapted to be secured to the lower end of a golf bag casing comprising a substantially inflexible insert member of curved outline, flexible covering for said insert

- 5 member fastened thereto and extending beyond the outline thereof, the extended portions of said covering extending upwardly perpendicularly to the plane of said insert member, a hollow cylindrical member of relatively rigid material having overlapping vertical edges, flexible covering for the outside surface of said cylindrical member from the uppermost to the lowermost edges thereof, said cylindrical member having its entire surface substantially perpendicular to the plane of said insert member and having its lowermost edge extending straight down past the upstanding edges of said insert member covering so that the lower portion of the inside surface of said covered cylindrical member tightly engages and surrounds the outside portions of
- 10
- 15

the upstanding edges of said insert member covering, a line of stitching passing through the outside face of said outside covering and sewing together the lower portion of said cylindrical member, the covering therefor and the upstanding edges of said insert member covering, and a line of stitching in continuation of said first named line of stitching sewing together the overlapping vertical edges of said cylindrical member, the upper portion of said cylindrical member being open and being adapted to receive interiorly thereof the lower end of a tubular golf bag casing, the said mentioned lines of stitching being visible from the outside of said golf bag bottom unit.
